UNITED STATES PATENT OFFICE.

IRVIN U. MINEHART, OF COGGON, IOWA.

DOOR-CATCH.

1,374,215.

Specification of Letters Patent. Patented Apr. 12, 1921.

Application filed February 3, 1920. Serial No. 355,915.

To all whom it may concern:

Be it known that I, IRVIN U. MINEHART, a citizen of the United States, residing at Coggon, in the county of Linn and State of 5 Iowa, have invented a new and useful Door-Catch, of which the following is a specification.

This invention relates to new and useful improvements in door catches or latches 10 and the object thereof is to provide improved gravity operated latch for use on barn doors or wherever a simple and durable catch is desired, as well as being adapted for use on ice boxes, refrigerators, or 15 other furniture.

A further object of the invention is to provide an improved catch or latch construction which obviates the necessity of employing springs or other complicated 20 parts likely to get out of working order, and in which the weight of the handles serves to hold the latch in secured position. The device embracing a few simple parts of 25 novel construction adapted to permit the latch to be reversed for right or left hand doors, while additional means are provided for holding the door in an open position while preventing injury to one of the handles which co-operates with means carried by a 30 wall or part against which the door moves when opened, in order to prevent injury to said handles.

With the above and other objects in view which will appear as the description proceeds, the invention resides in the combination and arrangement of parts and in the details of construction hereinafter described and claimed, it being understood that within 35 the scope of what is claimed, changes in the 40 precise embodiment of the invention shown can be made without departing from the spirit of the invention.

In the accompanying drawings:

Figure 1 is a front elevation of my improved gravity door catch in applied position, the bolt being shown engaged with its keeper;

Fig. 2 is an end elevation of the device disengaged from the keeper;

Fig. 3 is a vertical sectional view taken on the line 3—3 of Fig. 1 but showing the latch in a disengaged position;

Fig. 4 is a fragmentary perspective view showing the means of engagement with one 55 of the handles of the catch or latch, in order to hold the door in an open position;

Fig. 5 is a detailed view of an arbor or fulcrum bar for actuating the sliding bolt; and

Fig. 6 is a perspective view of the sliding bolt.

Referring to the drawings in detail, in which like reference characters designate corresponding parts throughout the several views, my improved door catch is shown as 65 comprising a casing 10 preferably of integral rectangular outline having attaching flanges 11 at the top and bottom edges thereof of suitably apertured for receiving securing screws or the like 12 by which the device 70 is attached to the outer face of a door or the like 13 adjacent to the free edge portion thereof. The casing 10 cut or hollowed out at its inner face as shown at 14 and in rectangular outline, providing side walls 15 75 and 16 the latter of which is provided with a recess or opening 17 for the purpose of receiving the engaging end of the sliding latch bolt therethrough, as will be later described. The inner face of the casting or the 80 like forming the casing 10 above and below the cut-out portion 14 provided with rabbeted portions or seats 18 adapted to accommodate a rectangular cover plate 19 which is suitably secured as indicated at 20 to the 85 casing, at the inner walls of the recesses or rabbeted portions 18, as particularly shown in Fig. 3 of the drawings. Alined openings 21 are provided in the front wall of the casing proper and the plate 19, so as to receive 90 an arbor or fulcrum bolt 22 having a radially projecting bit 23 preferably slightly tapered toward its free end as shown, and accommodated between the wall at the casing and the plate 19 with the arbor projecting 95 beyond the outer faces thereof. Slidably mounted in the cut-out 14 between the top and bottom walls thereof, is a sliding bolt or catch 24 of peculiar configuration preferably having corner projections 25 at the 100 enlarged end thereof which is provided with a series of corrugations as shown. At the tapered end of the catch plate or bolt 24, it is provided with a reduced catch portion or beveled ended bolt 26 forming end shoulders 27 at the top and bottom, designed to engage the inner face of the wall 16 through which the opening or recess 17 is provided to accommodate the portion 26.

As the sliding catch or bolt 24 is mounted 110 within the casing, it is designed to be normally engaged by the bit 23 and for this pur-

pose the said latch plate or bolt is provided with a cross shaped opening 28 therethrough having a series, preferably four recessed extensions 29 extending vertically and horizontally in either direction for engagement by and accommodating the bit 23. Mounted on the projecting ends of the arbor or fulcrum bolt 22, are handles 30, each having an opening 31 therethrough and formed at 10 one end with a reduced extension or hub 32 apertured to receive the arbor therethrough. The arbor is shown of circular cross section so as to freely rotate through the circular apertures 21 and the handles are fixed 15 or keyed to the arbor, as by means of screws 33 engaged through the reduced portions 32 at one side and seating in the arbor as shown. Obviously when these handles are raised in the manner shown in dotted lines in Fig. 2 20 of the drawings, they will swing the arbor on its pivot to cause the bit 23 operating in the lower extension of the opening 28, to slide the bolt 24 inwardly in the cut out, whereby to withdraw the end portion 26 25 into the casing part 10 and from within the opening of the keeper or catch escutcheon, which keeper is designated at 34, while the recess thereof is designated at 35. This recess or catch extends to the full height 30 of the cut out portion 14, thus obviating the possibility of the keeper being so displaced with respect to the door should the latter sag to prevent interference with the working of the latch. The keeper plate is 35 of elongated form having attaching flanges 36 at the upper and lower ends thereof suitably apertured for receiving fastening screws or the like 37 in juxtaposition to the casing 10. As the keeper plate is of right 40 angular cross section at the opening and cut out 35 forming the catch escutcheon, the open side is disposed toward the free end of the casing 10 at the wall 16 from which the bolt 26 projects and the wall 38 closes 45 the outer face of the keeper. By swinging the handles 30 to raised positions in the manner shown in Fig. 2 of the drawings, the bolt is withdrawn from the keeper and by reason of the weight of the handles, and 50 the beveled end of the bolt 26, the latter may be engaged with the keeper without injury to the parts, that is, automatically so as to raise the handles when the same are horizontally disposed due to the shifting of the 55 catch plate or bolt 24 through the medium of the arbor 22 and the bit 23, or the catch may be engaged with the keeper by raising the handles manually and then releasing them when the weight of the handles acting by 60 gravity will automatically dispose the catch in an engaged position. In this position displacement will be positively prevented, since the flat face of the bolt will be presented against the inner face of the front 65 portion of the keeper 34 and the door can

only be opened by raising the handles manually. Thus, the necessity of employing defective or complicated parts such as springs and other intricate constructions commonly employed in locks or the like and 70 catches, is obviated, thereby rendering the device especially adapted for use in connection with outside doors particularly barn doors, or in connection with refrigerators, ice boxes and the like where rusting is apt 75 to take place and injure intricate parts, such as springs and the like commonly employed in this art.

In order to hold the door in an open position against a wall or part of the 80 enclosure in which the door swings, the handle at the outer face of the casing is designed to engage a catch 39, the same being of V-shaped construction having attaching legs 40, the feet portions 41 of 85 which are disposed in alignment and slotted as indicated at 42, to receive adjusting screws 43 by which the catch is attached to the face of the wall 44. The catch 39 is provided with a beveled engaging portion 90 45 designed to permit the handle 30 at the outside to ride over the same, so that said beveled portion will engage between the spaced portions of the handle produced by the opening 31 in the form of an elongated 95 slot therein, and also forming a grip by which the handle may be conveniently manipulated, so that the right angular shoulder 46 will engage the inner wall of the one 100 of the spaced portions of the handle, thus preventing the door from swinging to a closed position until the handle at the opposite side is raised. It is understood that this engagement is automatic, especially 105 due to the fact that the handle 30 may be elevated by a beveled portion 45 in moving into engagement with the shoulder 46 in order to prevent injury to the handle, the catch is provided with an extension 47 at the free end thereof adapted to abut the 110 door or wall of the barn, as indicated particularly in Fig. 4 of the drawings. By reason of the slots 42 and the securing means 43, the catch can be vertically adjusted so as to accurately engage the handle. 115

It will thus be seen that I have provided a door catch or latch, which embodies a simple construction consisting of a few working parts which are simple to operate and not likely to get out of working order. 120 It obviates the necessity of employing springs in view of the gravity action thereof employed in connection with its operation and in view of the simple character of a few parts employed in construction, it 125 can be economically produced and sold. Also, by reversing the direction of the bit 23 of the arbor 22 to engage the lower recess 29 of the opening 28 when the casing is in a reversed position, the device can be 130

used for either right or left hand doors, the flat extension of the fulcrum bolt or arbor 22 constituted by the bit 23 corresponding to the bit of a key, always extending downwardly for operation of the bolt in the manner already explained. It is also to be understood that the handles are in reverse positions during this operation, simply by loosening the set screws or other 10 fastening means employed for securing the handles to the arbor, it being understood that the arbor may be squared or otherwise formed for this purpose. Since the extension or bumper 47 engages the door, and 15 the handle is engaged with the catch shoulder 46, the possibility of striking the handle against the wall and breaking the same, is obviated.

Having thus described the invention what 20 I claim is:

A door catch of the gravity type embodying a keeper having attaching means, a casing having attaching means, said keeper and casing conforming in shape in end elevation, said casing having a cut-out producing top and bottom walls and side walls, one of said side walls disposed toward the keeper being provided with a recess, said top and bottom walls being provided with 25

rabbeted recesses, a detachable cover plate 30 secured in said rabbeted recesses, over the cut-out at the back of the casing, a latch bolt of tapered-like formation movably mounted in the cutout, the enlarged end thereof being slidably supported at the bottom of the cut-out and the reduced end thereof being formed with a beveled engaging portion with shouldered walls above and below the same, said bolt having a cross shaped opening therethrough having a 40 series of extensions of concaved-formation extending vertically and horizontally, an arbor rotatably mounted through the casing and having a radially projecting bit 45 designed to engage said opening and extension recesses thereof whereby when the arbor is turned said bit engages the walls of said recesses to shift said bolt to engaging or disengaging positions with respect to the keeper, and handles mounted on the 50 arbor.

In testimony that I claim the foregoing as my own, I have hereto affixed my signature in the presence of two witnesses.

IRVIN U. MINEHART.
